UNITED STATES PATENT OFFICE

2,246,198

CONTAINER

Philip Zalkind, New York, N. Y.

Substitute for abandoned application Serial No. 61,856, February 1, 1936, which is a division of application Serial No. 692,937, October 10, 1933, which in turn is a division of application Serial No. 631,682, September 3, 1932. This application May 28, 1938, Serial No. 210,549

5 Claims. (Cl. 229—34)

My invention in this application which is a division of application Serial No. 692,937, filed October 10, 1933, and which is a division of application Serial No. 631,682, filed September 3, 1932, relates to containers and casings therefor and more specifically relates to drawers adapted to be pushed into and pulled from a casing made of suitable sheet material.

In general my invention embodies a container and casing combination made of sheet material such as cardboard or paper box board, corrugated board, fiber board, and/or any other material adaptable or adapted to be stamped and bent upon creased, scored, or otherwise formed on predetermined lines for the purposes herein-after described after the same has been suitably cut, creased, stamped or blanked out in outline form.

Drawers of the type described above, must be sufficiently rugged to withstand the strains to which they are subjected in being pushed into and pulled from a casing to justify their construction from sheet material of the type described above; they must be of low cost and be adapted for shipment in a collapsed state.

Accordingly, objects of my invention are: to provide means for making inexpensive and yet rugged containers of sheet material; to make novel containers adapted for shipment in a "knock-down" condition and arranged to be simply and easily assembled and erected by the user; and to make containers which in "knock-down" condition or collapsed condition lie substantially flat, so as to occupy a minimum space for shipping and storage.

In order to readily push and pull a drawer into and from a casing, it must obviously be provided with a handle. I have discovered a special mounting of the handle which not only insures a secure support therefor, but also does not interfere with the packing of the collapsed containers for shipment.

Accordingly, then, further objects of my invention are: to provide novel handle constructions for collapsible containers which do not interfere with the collapsing of the containers into a substantially flat unit; to provide a handle mounted in a novel depression formed in the front wall.

In pushing and pulling the drawer from its casing, it is subjected to shearing strains along the vertical edges of the front wall. I have discovered that by transferring these strains to the side walls, they can be distributed over a large area and are therefore less likely to be destructive of the container.

Accordingly, still further objects of my invention are to provide: a container having a novel bracket extending from the end wall to the side walls for securing them to each other; side walls secured to end walls by snap fasteners, etc.

Other objects of my invention are to provide in my novel collapsible container; reinforcing blanks for aiding in holding the end and side walls to each other; means for producing smooth flush surface between the overlapping tongues and side walls.

There are other objects of my invention which together with the foregoing will appear in the detailed description of the drawing which is to follow in which:

Figure 1 shows a blank or development made from a sheet of material and adapted to be formed or folded into a container or file drawer having the side walls and tongues thereof secured by means of adhesive strips or the like laced through suitable perforations formed therein.

Figure 2 is a view in perspective showing a partially assembled or folded drawer made from the blank shown in Figure 1.

Figure 3 is a fragmentary perspective view of one corner of the drawer before the extension of the side wall is folded against the inside of the tongues and side wall and before the securing tape is inserted in the perforation therein.

Figure 4 is a detailed view of a modified form of perforation formed in the front wall to receive an ear or lug formed on the extension of the side wall.

Figure 5 shows the manner of securing a strengthening channel strip to the side walls of a drawer like that shown in Figure 2.

Figure 6 illustrates a modified form of joint between the side wall and tongues formed by a piece of gummed tape or the like.

Figure 7 is a view in perspective showing a modified form of drawer partially assembled.

Referring now to the drawing described above, and particularly to Figure 1 thereof, wherein I illustrate a blank from which a container of the class described may be constructed from a single sheet of suitable material, it will be understood that the material is first cut, scored, stamped or blanked in any suitable manner.

As shown, I provide reinforcing strips of the material of the container for stiffening the side walls thereof and for securing the tongue in position.

The blank is cut or stamped out and creased on lines 1, 2, 3, 4, 5, and 6 to form a bottom 7,

sides 8, and enveloping or stiffening extensions or side wall extensions 9 lying beyond the creases 5 and 6 respectively for a purpose to be herein-after described. The blank also comprises a rear wall 10, and a tongue 11 extending from each side thereof. The tongues may be more particularly defined as lying beyond the creases 1 and 2 respectively, and cut edges 12 and 13 which separate the tongues from the side walls 8 and extensions 9. It will also be seen that at each end of the extension 9, I form a lug or ear 14 from material cut from the lower edge of the tongue 11. The portion of the blank adapted to form the front end of the drawer is similar to the portion adapted to form the rear end thereof, just described, and comprising tongues 15 disposed at each edge of a front wall 16, see Figure 2, in which is cut a perforation 17. In Figure 1, I show an auxiliary front wall piece 18 having exactly the same shape as the front wall 16 except that the tongues on the auxiliary wall are shorter than the tongues 15 and extend only from wall 18 to the point designated by the numeral 19. A handle 20 is adapted to be secured to the auxiliary wall 18 in a position to permit one to grasp it through the perforation 17 in the front wall when the auxiliary wall is placed in the position shown in Figure 1 and the blank is formed into a drawer or container.

From Figures 1 and 2 it may be understood that the thickness of the material from which the drawer is made is substantially equal to the thickness of the handle whereby the auxiliary wall 18, and the handle secured thereto, are adapted to lie flat on the front wall 16, i. e., in surface contact therewith and in substantially the same plane as wall 16 to facilitate the packing and shipment of the blanks. The sides 8 are perforated as shown at 21 and the tongues are perforated at 22. The rear wall 10 and auxiliary wall 18 are perforated as shown at 23 and 24 respectively, to receive the ears 14 on the extensions 9 in a manner to be described hereinafter. A section of material is also cut away for a short distance along the lines 5 and 6 between the walls 8 and extensions 9 to form notches 25 and 26 respectively. The side wall extensions 9 are scored at 27 to facilitate bending the same over the tongues 11 and 15 as herein-after described. Strips of paper or muslin 28, carrying adhesive material are secured to the extensions 9, as shown in Figure 1, to secure the parts of the drawer in position when it is folded as herein-after described. Said strips 28 may of course, be carried by the tongues of the end wall or of the auxiliary wall, or by the bottom wall of the container or by any other portion of the container on which they may be mounted; and may even be supplied separately for use as herein-described.

Thus, as in Figure 7, the tape 28' may be carried by the tongue 11. In setting up the container, the tape 28' may be threaded first through the slot 22 in the tongue, through the slot 21 in the side wall, around the upper edge of the side wall and adhesively secured on the inside of the wall, against the attached end of the tape or against the lower portion of wall 8.

Referring now to Figure 3, it will be seen that the rear wall 10 and tongue 11 may be bent to form the end of the container and that the wall 8 is bent up to lie flat against the outside of the tongue 11. In this position, the perforations 22 in the tongue will register with the perforation 21

in the wall 8 and provide an opening through which the strips 28 may be inserted and thereafter wrapped around the extensions as many times as desired and adhesively secured to the container.

It will be seen, however, that before the strips 28 are adapted to enter the perforations 21-22 that the extension 9 must be bent inwardly over the top of the tongue 11 such that the inner end 10 of the notch 25 will register with what I shall describe as the apex 29 of a reentrant angle formed in the tongue 11. It will also be understood that when the extensions 9 are folded into position and the strips 28 are adhesively secured to the outside of the container or wrapped around the extensions 9 as described, that the ears or lugs 14 will fit into perforation 23 as shown in Figures 2 and 3 to hold the ends of the extension securely in position. Figure 2 illustrates clearly the manner in which the container may be assembled and also shows the auxiliary front wall 18 carrying the handle 20 in registration with the perforation 17 in the front wall 16.

In Figure 4, I illustrate another manner in which the notches 23 may be made. Instead of actually punching out a section of material, as will be understood in connection with the holes 23 above described, the material may be merely cut along lines 30 adjacent the crease 31 so that when the material is bent at right angles a portion 32 will project from a line coincident with the crease as shown and leave a perforation 33 into which the ends 14 may extend.

I may provide a channel strip 34, of U-shaped cross-section, adapted to fit over the upper edge of the wall 8, tongue 11, and extension 9 to still further stiffen the assembled drawer, if desired, as shown in Figure 5.

For instance in the form of container shown in Figure 2, the side wall extensions 9 may be made narrower as shown at 36, Figure 5, so that a lip or flange 35 on the clip 34 will engage the edge of the extension when the clip is in position on the edge of the side wall. The clip is secured in position by first hooking the lip 35 under the edge of the extension 36 and thereafter rotating the clip from the position shown in dotted lines, Figure 5, to that shown in full lines in said figure. It will be understood that if the parts are properly proportioned, only a little pressure is required to affix the clip to the material.

Referring now to Figure 6, it will be seen that I contemplate strips of adhesive tape 37, adapted to extend from the bottom of the drawer up the side and over the tongue 11 which may be used to fasten the wall and tongue together. As shown in this figure the extension 9 has been omitted and the tongue 11 is placed on the outside of the side wall 8. The adhesive strips 37 may be formed with extensions 38 adapted to be glued to the outside of the wall 8 and cover the end of the tongue 11 remote from its juncture with the wall 10.

From the above description, it will be seen that a drawer like that shown in Figure 2, made from the blank shown in Figure 1, comprises a front wall 16, adapted to be subjected to transverse strains in being pushed into and out of a suitable container and that said wall is supported by and secured to side walls 8 of the drawer by tongues 11 adapted to be suitably fastened to the side walls to transmit said strains to the said walls in the form of tensile strains when the drawer is pulled open; and compressive strains when the drawer is pushed closed.

This application is a substitute for my abandoned application, Serial No. 61,856, filed February 1, 1936.

Although I have herein illustrated various applications of my invention, it will be understood by those skilled in the art that it may take other forms and I do not wish to be limited thereby except as set forth in the appended claims.

I claim:

1. In a collapsible container; an end wall; side walls; tongues extending from said end wall and engaging said side walls; an extension on said side walls overlapping said tongues; and means engaging said side wall and said extension for securing said tongues and said side wall to each other said means comprising an adhesive tape carried by said container and extending therefrom passing through registering openings in said tongues and said side wall.

2. In a collapsible container; an end wall; side walls; an auxiliary end wall piece; tongues extending from said end wall and said auxiliary end wall piece and engaging said side wall; slots in said side wall; corresponding slots in said tongues; and an adhesive tape carried by said side wall and extending therefrom passing through registering slots in said side wall, said tongue on said end wall, and said tongue on said auxiliary end wall piece, for securing said side wall and said end wall to each other.

3. In a collapsible container; an end wall; side walls; an auxiliary end wall piece; tongues extending from said end wall and said auxiliary end wall piece and engaging said side wall; slots

5 in said side wall; corresponding slots in said tongues; and an adhesive tape carried by said tongue on said end wall and extending therefrom passing through registering slots in said side wall, said tongue on said end wall, and said tongue on said auxiliary end wall piece, for securing said side wall and said end wall to each other.

4. In a collapsible container; an end wall; side walls; an auxiliary end wall piece; tongues extending from said end wall and said auxiliary end wall piece and engaging said side wall; slots in said side wall; corresponding slots in said tongues; and an adhesive tape carried by said tongue on said auxiliary end wall piece and extending therefrom passing through registering slots in said side wall, said tongue on said end wall, and said tongue on said auxiliary end wall piece, for securing said side wall and said end wall to each other.

5. In a collapsible container, an end wall; side walls; tongues extending from said end wall and engaging said side walls; an extension on said side walls overlapping said tongues; said extension on said side walls being of less height than said side walls and extending partially down said side walls when said container is erected, means for securing said container in erected condition; said means comprising adhesive tape carried by said extension and extending therefrom and passing through registering openings in said tongue and side wall.

PHILIP ZALKIND.
